UNITED STATES PATENT OFFICE.

THOMAS KENNEDY WHITE, OF HURON, SOUTH DAKOTA.

SCOOP CLEANER.

Application filed March 26, 1925. Serial No. 18,483.

This invention relates to scrapers to be employed in connection with scoops of excavating machines, the primary object of the invention being to provide simple means whereby the inner surfaces of the scoops may be scraped to remove the contents thereof, and prevent the earth dug by the scoops from adhering to the scoops.

Another important object of the invention is to provide a movable scraper which will be actuated automatically by the movements of the links of the chain supporting the scoops, eliminating the necessity of providing pivoted arms or the like for operating the scraper.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 a longitudinal sectional view illustrating a length or chain carrying scoops and scrapers constructed in accordance with the invention.

Figure 2 is an enlarged plan view of a scoop and scraper.

Figure 3 is a modified form of scoop cleaner.

Referring to the drawing in detail, the reference character 5 indicates links of a supporting chain to which the scoops 6 are secured.

The scoops are of the usual construction and embody digging prongs 7 which are secured to the forward edges of the scoops in the well known manner.

The scrapers forming an important feature of the invention include bars curved intermediate their ends to provide a curved scraping surface 8 conforming to the curvature of the scoops in which they operate.

By forming the scrapers, in a manner as described, arms 9 are provided, which arms are relatively long and are formed with

openings arranged in spaced relation with the ends thereof, which openings accommodate the bolts 10, while the ends of the arms 9 are formed with openings to accommodate the bolts 11 whereby the scraper is securely held to the links of the chain.

It might be further stated that scoops as shown and described, when supported on endless chains operate over suitable sprockets indicated at 12, to the end that as the chain passes over the sprocket, the arms of the scraper move downwardly with one link of the chain, moving the scraping portion thereof over the inner surface of the scoop supported adjacent to the link supporting the arms. In order to increase the efficiency of the scraper, the forward edge thereof is beveled as at 13 to cut into the material picked up by the scoop.

In the form of the invention as illustrated by Figure 3 of the drawing, the scraper includes a pair of scraping blades 14 that are pivotally supported adjacent to the scoop 15, the pivot point being indicated at 16. An arm indicated at 17 is formed integral with the blades and extends to a position beyond the chain supporting the scraper so that the arm lies in a position to engage the bar 18 supported under the chain to the end that as the arm moves over the bar 18, the scrapers are operated through the scoop to clean the scoop.

Associated with the arm of each scraper is a coiled spring 19 which is adapted to return the scraper to its initial position after it has been moved through the scoop.

From the foregoing it will be obvious that the scoops indicated at A and which will be filled with material and that as the chain passes over the sprocket 12, the scraper moves with the link to which it is secured moving the scraping surface thereof throughout the length of the scoop, to a position as indicated at B in Figure 1.

It will thus be seen that the material is scraped from the scoop and released therefrom.

I claim:

In a device of the character described, supporting chains, scoops secured to the supporting chains, scrapers including elongated

gated members bent intermediate their ends providing curved scraping surfaces conforming to the curvatures of the scoops, said scrapers being pivotally secured to the 5 chains at points intermediate the ends of the scrapers, and said scrapers having their outer ends secured to the links of the chain

at points in spaced relation with the first mentioned securing points of the scrapers.

In testimony that I claim the foregoing 10 as my own, I have hereto affixed my signature.

THOMAS KENNEDY WHITE.
